MADELEINE BERSIN, OF COLONIA DEL VALLE, MEXICO

SWADDLING CLOTH

Application filed June 12, 1928. Serial No. 284,800.

This invention relates to improvements in swaddling cloths and has for one of its objects to provide an improved device of simple and practical construction designed to replace the diapers ordinarily employed for infants.

Another object is the provision of a swaddling cloth which may be easily and quickly adjusted in position without the use of safety pins and which will be securely held in proper position on the body of a child.

The above and other objects will appear more clearly from the following detailed description, when taken in connection with the accompanying drawing, which illustrates a preferred embodiment of the inventive idea.

In the drawing—

Figure 1 is a plan view of the swaddling cloth constructed in accordance with the invention; and

Figure 2 is a perspective view showing the cloth in adjusted position.

Referring more particularly to the drawing, 3 indicates generally the body of cloth which may be made from a single piece of any suitable material and in any desired size. The body is cut to form front and back sections 4 and 5 and an intermediate or crotch section 6 which is disposed between the legs 30 of the child when in position on the body. The intermediate section is preferably reduced in width as compared to the front and back sections and this is accomplished by cutting the material along its longitudinal 35 edges on inwardly curved lines so that the front and back sections will taper inwardly toward the section 6. The ends of the body 3 forming the outer ends of the sections 4 and 5 are cut on outwardly curved lines so that said sections will adequately cover the stomach and lower portion of the back of the child.

At the four corners of the body 3 the same has attached thereto the ribbons or other 45 flexible securing means 7, 8, 9 and 10, which

are utilized to fasten the cloth in its proper position and prevent it from slipping down on the body when being worn. Slots 11 and 12 are formed in the body adjacent the corners to which ribbons 8 and 10 are secured 50 and are designed, respectively, to have the ribbons 7 and 9 passed therethrough as will presently appear.

Secured to the inner surface of the body 3 in any suitable manner is an absorbent pad 55 13 of towel cloth or other soft material. This pad extends longitudinally of the body 3 and practically covers the intermediate section 6, it being made in any suitable shape best suited for its purpose.

In practice, the front section 4 is first laid upon the stomach of the child in proper position and the ribbon 7 is then extended around the back, passed through the slot 11 in the opposite corner of the section, and then brought to the front. The ribbon 8 is simply extended around the back and to the front where it is tied to the ribbon 7 over the stomach. The intermediate section 6 is then passed between the legs, and the back section 5 then brought upwardly to partially cover the back. The corners of said back section are then drawn forwardly over the stomach after which the ribbon 9 is extended through the slot 12 and rearwardly over the outer surface of said section. Ribbon 10 is then passed about the section 5 in a direction opposite from the ribbon 9 and around toward the back where it meets the latter ribbon and the two ends are then tied together. The operation is now completed and the cloth is, in this manner, secured in position and will not slip down on the body or legs of the child as is so often the case with the ordinary diapers.

What is claimed is:

A swaddling cloth including tapered front and back sections, the outer ends of which are cut on outwardly curved lines, an intermediate section connecting the front and

back sections, and opposed flexible elements secured to the corners of the front and back sections, said sections having slots adjacent the corners thereof on the same side of a medial longitudinal line through the cloth, one of the flexible elements of each section extending through the slot adjacent the opposite corner of said section around the body of a child in one direction, and the other element of each section being extensible about the body in an opposite direction and secured to the first named element of said section.

In testimony whereof, I have affixed my signature.
